UNITED STATES PATENT OFFICE.

HENRY J. SMALL, OF SAN FRANCISCO, AND OTTO B. SCHOENKY, OF SACRAMENTO,
CALIFORNIA, ASSIGNORS TO WALTER P. MURPHY, OF CHICAGO, ILLINOIS.

CAR-ROOF.

1,128,067.

Specification of Letters Patent.

Patented Feb. 9, 1915.

Application filed February 25, 1913. Serial No. 750,546.

To all whom it may concern:

Be it known that we, HENRY J. SMALL, of San Francisco, in the county of San Francisco and State of California, and OTTO

5 B. SCHOENKY, of Sacramento, in the county of Sacramento and State of California, have jointly invented a certain new and useful Improvement in Car-Roofs, of which improvement the following is a specification.

10 Our present invention relates to metallic roofs, which are more particularly designed for use in railroad cars, but are also adaptable for application in other structures, and are of the general type exemplified in Letters Patent of the United States No. 986,093, granted and issued to us under date of

15 March 7, 1911.

The object of our invention is to provide, in a metallic roof of such type, improved 20 means for effecting the connection of the roof sheets to the side and end plates of a car, whereby the access of water to the inside of the car will be effectually prevented and proper ventilation of the car permitted.

25 The improvement claimed is hereinafter fully set forth.

In the accompanying drawings: Figure 1 is a partial half plan view of a car roof embodying our invention; Fig. 2, a vertical 30 longitudinal central section; Fig. 3, a half vertical transverse section; Fig. 4, a similar partial perspective section, on an enlarged scale, on the line *a a* of Fig. 2; and, Figs. 5 and 6, partial transverse sections, on a 35 similar scale, on the lines *b b* and *c c*, respectively, of Fig. 2.

In the practice of our invention, we provide a plurality of roof sheets or plates of metal, 1, sufficient in number for the length 40 of roof required, and of proper length for connection, at their ends, to the side plates, 5, of a car, as hereinafter described. The roof sheets, which extend continuously across the car, are connected one to another, on 45 their adjoining sides, by rows of rivets, 1^a, and are arched or curved throughout their length, transversely to the car, and a longitudinal corrugation, 1^b, is formed in each sheet, said corrugation, which constitutes a 50 transverse arching of the roof sheet, diminishing in depth from the longitudinal center line of the roof to the sides thereof, at or near which it terminates by merging into the surface of the roof plate. The corruga- 55 tions, 1^b, perform the functions of the car-

lines ordinarily employed, which are wholly dispensed with, and enable the roof to be self supporting.

The upper ends of the side plates, 5, are curved slightly outwardly, in order to deflect any water that may tend to enter from the outside, and the ends of the roof sheets are bent downwardly into vertical eaves, 1^c, which are located a short distance outside of the side plates, so as to be spaced apart 60 therefrom, and depend below the curved upper end portions thereof. The bodies of the roof sheets are located a short distance above the tops of the side plates, so as to be separated therefrom by a continuous open 65 space. The form and relative location of the roof sheets and side plates, as above described, will clearly appear by reference to Figs. 4, 5, and 6.

The middle portions of the ends of the 75 roof sheets are connected to the side plates by horizontal rivets, 6, passing through short fillers or spacing pieces, 7, interposed between the eaves, 1^c, and the side plates, one of said fillers being provided at each end 80 of each roof sheet, at the middle thereof. As shown in Figs. 2 and 4, the fillers are in the form of metal plates, doubled over at and near their tops, to be equal to the width 85 of the space between the eaves and the side plates, but castings or forgings of corresponding thickness may obviously be used, if preferred. At the laps of the roof sheets, one on another, their spacing, relatively to the side plates, and their connection therewith, are, as shown in Figs. 5 and 6, similarly maintained and effected, the fillers, at these points, being in the form of ferrules or thimbles, 7^a, interposed similarly to the plate fillers, 7, but in line with the rows of 90 rivets, 1^a, connecting the roof sheets, the rivets, 6, passing through said ferrules, and through the eaves of two adjoining roof sheets and the adjacent side plate, and being headed over at their ends on the latter 95 and on the overlapping roof sheet. The spaces between the several fillers, on each side of the roof, are open at bottom to the external atmosphere, and open at top to the interior of the car, thus affording free passage of air for the ventilation of the car.

The end roof sheets are connected to the end plates, 8, of the car, by rivets, 6, passing through fillers, 7, of the form first specified. 100

The roof herein set forth is simple, strong, and inexpensive, and is particularly advantageous in the particulars of permitting ample ventilation of the car, preventing the access of rain to the lading, and preventing water of "sweating" or condensation on the inside of the roof sheets from dropping into the car, the roof sheets being unobstructed to the exterior of the side plates, so that such water is led to and discharged on the outside of the car.

We claim as our invention and desire to secure by Letters Patent:—

1. In a freight car, metal roofing sheets extending from eaves to eaves of the car, the ends of the sheets terminating in vertical eaves portions located a short distance outside of the side plates, and filler blocks secured to the side walls of the car at intervals throughout the length of the car, and of a thickness equal to the space between the side walls and said bent down ends of the sheets, and means securing said down turned ends to said filler blocks, whereby the roofing sheets are supported solely from the sides of the car and spaced from the top and side of said side walls with an uninterrupted ventilating space extending throughout the length of the car between the underface of the roof and the top of the car wall.
2. In a car, metal load sustaining roofing sheets extending from eaves to eaves of the car, the end portions of the sheets extending beyond the side walls of the car and bent downward with spaces between them and the side walls, and means secured to said down turned ends and to the outer face of the car wall and exclusively supporting said sheets from said wall with a ventilating space between the sheets and said side walls.
3. In a car, a roof comprising load sustaining metal sheets extending from eaves to eaves of the car and means constituting the exclusive support of the sheets secured to the sides of the car, said means support-

ing the sheets with a ventilating space between them and the top and side of the side wall.

4. A car consisting of metal side and end walls, a roof composed solely of metal sheets extending from eaves to eaves with their outer ends extending beyond the side walls and bent down with a space between them and the side walls, said roof being wholly supported by means connecting said bent ends to the outer face of the side walls and holding said ends away from the side walls and the body of the sheets away from the top of the side walls whereby a ventilating space is maintained between the sheets and side walls, the ventilating space between the underface of the roof sheets and the top of the car wall being uninterrupted throughout the length of the car.

5. In a car, the combination, with vertical sheet metal side plates, the upper edges of which are slightly curved outwardly, metal roof sheets extending transversely of the car, each sheet having a strengthening rib pressed up therein to take the place of car lines, the ends of said sheets being bent down over the tops of said side plates without coming in contact therewith, and means to secure said ends to said plates so as to hold them apart both vertically and horizontally, whereby a ventilating air space is provided between the sides of the car and the roof, the ventilating space between the underface of the roof sheets and the top of the car wall being uninterrupted throughout the length of the car.
